BLADE HOLDING MEANS FOR HACKSAWS
AND THE LIKE

Dwight E. Priest and Harry P. Macomber,
Worcester, Mass., assignors to Parker Wire
Goods Company, Worcester, Mass., a corpora-
tion of Massachusetts

Application February 5, 1937, Serial No. 124,278

1 Claim. (Cl. 145—33)

The present invention relates to the construction and manufacture of the devices which are associated with a hack saw frame and which serve for the holding and tensioning in said frame of the saw blade. Our invention provides a one-piece blade retaining device which affords a maximum width of bearing surface for the end of the blade and, at the same time, is readily insertable in the squared socket or other receiving means therefor provided by the end of the hack saw frame; our invention contemplates the manufacture of such retaining devices from headed bolts or rivets of substantially conventional type. Other and further objects and advantages of the invention will be made apparent in the following detailed description thereof, reference being had in this connection to the accompanying drawing, wherein

Fig. 1 is a perspective view of one of the headed bolts or rivets, of substantially standard form, used in the manufacture of my improved retaining device.

Fig. 2 is a perspective view illustrating the usual blade-retaining device as made from the bolt or rivet of Fig. 1.

Fig. 3 is a perspective view, illustrating the results of upsetting and drawing operations performed on the bolt or rivet of Fig. 1, to provide the retaining device of our invention.

Fig. 4 is a similar view of the blade retaining device shown by Fig. 3, as seen from the other side.

Fig. 5 is a fragmentary view illustrating a portion of a hack saw frame, with the device of Fig. 3 used therein.

Fig. 6 is a fragmentary large scale view illustrating the act of inserting our improved retaining device in said frame.

Like reference characters refer to like parts in the different figures.

Referring first to Fig. 1, there is shown a substantially conventional bolt or rivet having a head 1 and a shank 2, as the stock from which our improved blade-retaining device is fashioned.

One step in the manufacture of this bolt or rivet, forming no part of our present invention, is the formation on shank 2, immediately adjacent the underside of head 1, of a squared section 3 which, as hereinafter described, is matched by a square aperture or socket of the hack saw frame. In the ordinary manufacture of a blade-retaining device from the bolt or rivet of Fig. 1, the latter's shank 2 is slabbed or flattened off as shown at 4, Fig. 2, substantially on a diameter of said shank 55 and in a plane that substantially bisects the

squared section 3 and parallels two opposite sides of the latter. A pin 5, driven into the material of shank 2, projects outwardly from the slabbed-off surface 4 and is adapted, in the usual manner, to be detachably engaged by a hole formed in one end of the saw blade, the latter, when so engaged with pin 5, bearing flatwise at said end against the flat or slabbed-off surface 4 of the retaining device, as shown by the broken lines in Fig. 2.

With this conventional blade-retaining device shown by Fig. 2, the bearing surface 4 is so limited in width that it affords very little resistance to tipping or turning of the blade, when the saw is in use. In such cases where a greater width of bearing surface was desired, it has been the practice (see Fig. 1 of Priest Patent No. 2,058,107, October 20, 1936) to first insert the slabbed-off bolt shank through a squared aperture of the saw frame, and then, by a suitable flattening or pressing operation, to widen such slabbed-off shank portion; either that, or to provide a blade-retaining member with a wide bearing surface and an unheaded shank portion, the latter being headed over after insertion through the squared aperture of the saw frame; in either case, the retaining member, by enlargement of one end or the other after insertion in the frame aperture, becomes an inseparable part of the saw frame.

However, with a retaining member of the separable type herein dealt with, the bearing surface for the blade has always been relatively narrow or limited in width, primarily because the width of surface 4, being the maximum cross sectional dimension of shank 2, was accepted as the limit of stock width capable of passing through the saw frame's squared socket or aperture, (marked 6 in Figs. 5 and 6), that receives the squared section 3. Our invention overcomes these difficulties by providing a blade-retaining device made from the bolt or rivet of Fig. 1, but having an effective bearing surface appreciably wider than the diameter of shank 2, thus minimizing the tendency of the saw blade to tip or turn when in use; at the same time, the ability of the retaining device to pass through the squared aperture or socket 6 of the saw frame is fully preserved.

According to our invention, the material of shank 2, instead of being slabbed off in the usual way as shown by Fig. 2, is subjected to a swaging, 50 pressing and drawing operation, the effect of which, as best illustrated by Figs. 3 and 4, is to transform or change the outer end of said shank from a circular cross section to a substantially triangular cross section, the latter having two of

its sides in flat elongated equal-width surfaces 7 and 8, Fig. 4, that stand substantially at right angles to each other, and having its third side or hypotenuse in a third flat surface 9, Fig. 3, which 5 occupies a plane that substantially bisects the squared section 3. This operation involves no cutting off or discarding of any of the stock of shank 2; although there is an excess of stock on account of the reduced thickness of the shank's 10 cross section in this zone of flattening, a part of such excess is utilized along the longitudinal edges of surface 9 in increasing the width of said surface, and the remainder of such excess stock is utilized in drawing up from said surface 9 the 15 integral projection 10, for engagement with the usual hole in the end of the saw blade.

Although the surface 9, against which the saw blade bears, is thus given a width appreciably greater than in previous devices of this character, 20 and appreciably in excess of the height or width of the square hole or socket 6 of the saw frame, still this is no obstacle to the free passage through said hole or socket 6 of the blade retaining device of our invention; the reason for 25 this being that the width of surface 9 does not exceed the diagonal dimension of said square hole or socket 6. In consequence, as shown in Fig. 6, to effect the insertion endwise of our improved blade-retaining device through the usual square 30 hole or socket 6 of the saw frame, said surface 9 is presented diagonally or cornerwise to said hole, this being permitted by the companion flat surfaces 7 and 8 of the triangular cross section that coincide substantially with two adjacent right-angle edges of said hole or socket 6; thereupon, 35 the inward movement of the retaining device in this position is continued until the shank's round part 11 reaches the hole 6, at which time the shank is turned on its axis through 45° to 40 register the squared section 3 thereof with the squared hole or socket 6 of the saw frame. The hole 6, as is usual in devices of this character, cooperates with the squared section 3 of the device to prevent the latter from turning axially, when

operatively associated with the saw frame. Thus our improved device affords the usual opportunity for angular adjustment of the saw blade in the frame, by retracting the squared section 3 from the aperture 6, and then turning the device about 5 its longitudinal axis to dispose the bearing surface 9 in either a horizontal or a vertical position, as desired.

Our improved blade-retaining device affords definite economies in manufacture over previous 10 devices of this character, wherein the blade-engaging projection or pin, as a separate part, had to be inserted in and secured to the device. In our improved device, said blade-engaging projection is integral, being formed from the material of the shank itself, and it rises from a bearing 15 or supporting surface whose appreciably increased width, obtained as above described, affords much greater resistance than the bearing surfaces of previous blade-retaining devices to 20 forces tending to tip or turn said blade, or to disengage it from said projection.

We claim:

In a hack saw, a frame, and a blade holder separable from said frame and comprising a shank 25 having at one end an integral head and near the other end a laterally projecting blade-engaging pin, said shank being receivable in a regular polygonal saw-frame aperture of more than three sides and of such size as to exclude said head, 30 and said shank adjacent said head comprising an intermediate reduced section of a size smaller than said aperture and an end portion of polygonal cross-section fitting said aperture and preventing turning of the holder therein when said head abuts 35 the frame, the shank portion in the zone of said pin presenting a substantially flat blade-contacting surface from which said pin projects, and said surface having a width so much greater than the shank diameter as to require its cornerwise presentation to the saw-frame aperture, for passage 40 of said shank portion therethrough.
